(57) **CLAIM**

The ornamental design for a storage container for storing a dental implant fixture, as shown and described.

DESCRIPTION

FIG. 1 is a front view of a storage container for storing a dental implant fixture showing our new design;

FIG. 2 is a rear view thereof;

FIG. 3 is a right side view thereof;

FIG. 4 is a left side view thereof;

FIG. 5 is a plan view thereof;

FIG. 6 is a bottom view thereof;

FIG. 7 is a reference perspective view illustrating a state in which the cap member is removed from the storage container body thereof;

FIG. 8 is a reference perspective view illustrating a state in which the implant fixture is stored thereof; and,

FIG. 9 is an exploded view of the components including the implant fixture.
